(57) **CLAIM**

The ornamental design for a bottle, as shown and described.

DESCRIPTION

FIG. 1 is a front isometric of a bottle in accordance with the invention.

FIG. 2 is a front elevation of the bottle of FIG. 1; and, FIG. 3 is a top plan of the bottle of FIG. 1.

The sides that cannot be seen in the Figures are identical to those shown in the drawing. The bottom does not form a part of the design.
